UNITED STATES PATENT OFFICE.

LOUIS B. LINKMAN, OF CHICAGO, ILLINOIS, ASSIGNOR TO M. LINKMAN & CO., OF CHICAGO, ILLINOIS, A CORPORATION OF ILLINOIS.

SMOKING PIPE.

Application filed May 1, 1922. Serial No. 557,696.

To all whom it may concern:

Be it known that I, LOUIS B. LINKMAN, a citizen of the United States of America, and a resident of Chicago, county of Cook, and 5 State of Illinois, have invented a new and useful Improvement in Smoking Pipes, of which the following is a specification.

This invention relates to smoking pipes.

The main objects of this invention are to 10 provide improved means for reinforcing the slip-joint connecting the stem or mouth piece with the stummel; and to provide a reinforcing element of the above character which is adapted for use as a cleaner, with 15 the mouth piece serving as a handle, for cleaning the bowl of the pipe when the mouth piece has been removed from the stummel, and which also serves to collect moisture and nicotine.

20 An illustrative embodiment of this invention is shown in the accompanying drawings wherein—

Figure 1 is a longitudinal, vertical section of a pipe embodying this invention.

25 Fig. 2 is a plan of the mouth piece, showing the reinforcing and cleaning element attached thereto.

The present invention is an improvement over the invention set forth in my Patent 30 No. 1,104,203, issued July 21, 1914. The pipe illustrated in said patent includes the usual briar stummel and hard rubber mouth piece or stem. Seated in the bore of the mouth piece, at the inner end thereof, is a metallic tube for reinforcing the slip-joint nipple which connects the mouth piece with the stummel.

The present invention resides in an improved form of reinforcing tube which projects beyond the inner end of the mouth piece stem for collecting moisture and nicotine and is formed to provide a scraper for use in cleaning the bowl of the pipe.

40 In the form shown, the invention is applied to a smoking pipe including a briar stummel 1, and a hard rubber mouth piece 2. The stummel 1 includes the usual bowl 3, and shank 4. The shank 4 is provided with a longitudinally extending bore 5 communicating with the bowl through a re-

stricted passage 6. On the end of the shank 4, is the usual metallic ferrule 7. The mouth piece 2 comprises the stem 8 having a longitudinally extending bore 9, and being reduced at its inner end to form a slip-joint nipple 10 for engagement with the bore 5 of the stummel 1.

In the form shown, the reinforcing and cleaning element, which embodies this invention, comprises a metallic tube 11, having a bore which is substantially the same as the bore of the mouth piece. The reinforcing tube is attached to the mouth piece during the process of molding the stem 8, and is arranged so as to extend through the 55 nipple 10 and the adjacent part of the stem 8. The part of the tube 11, which is embedded in the material of the stem 8, is provided with a roughened surface so as to firmly grip the hard rubber stem. The tube 60 11 projects beyond the reduced end of the stem 8, so as to extend into the bore 5 of the stummel 1, and, at the end of the projecting part, the tube is formed to provide a scraper 65 12 which is adapted for use in cleaning the 70 bowl 3.

When the metallic tube 11 is used as a cleaner, the mouth piece 2 is removed from the stummel 1 and the stem 8 then serves as 75 a handle for the scraper 12.

Although but one specific embodiment of this invention has been herein shown and described it will be understood that certain details of the construction shown may be altered or omitted without departing from 80 the spirit of this invention as defined by the following claim.

I claim:

A mouth piece for smoking pipes comprising a longitudinally bored stem having 90 one end reduced to form a nipple, and a metallic tube secured in the bore of said nipple and an adjacent part of said stem for reinforcing said reduced end, said tube projecting beyond said nipple and having an 95 annular cleaning flange at its end.

Signed at Chicago this 28 day of April 1922.

LOUIS B. LINKMAN.
